UNITED STATES PATENT OFFICE.

BARTOL TRAVAGLIA, OF CAMPELLO, MASSACHUSETTS.

LIFE-SAVING APPARATUS.

1,152,242.

Specification of Letters Patent. Patented Aug. 31, 1915.

Application filed April 20, 1914. Serial No. 833,046.

To all whom it may concern:

Be it known that I, BARTOL TRAVAGLIA, a citizen of the United States, and resident of Campello, county of Plymouth, Commonwealth of Massachusetts, have invented an Improvement in Life-Saving Apparatus, of which the following description, in connection with the accompanying drawings, is a specification, like characters on the drawings representing like parts in each of the several views.

This invention relates to life saving apparatus and particularly to life saving floats into which persons may be received in case 15 of disaster at sea and which will be secure against danger of sinking until picked up by succoring ships.

In accordance with my invention I form float structures adapted to be effectively 20 closed against the entrance of water and having provision to insure a sufficient supply of air for the inmates notwithstanding the possible tossing about of the float on the waves.

25 In accordance with one form of my invention I provide ballasting means adapted to keep the float substantially upright, or to quickly right it after being tilted.

In accordance with another form of the 30 invention I construct the float so that it is equally habitable and sea-worthy either side up so that even if it turns over, the inmates experience no other discomfort than being transferred from one side of the float to the 35 opposite one.

The invention will be better understood from the following detailed description taken in connection with the accompanying drawings and will thereafter be pointed out 40 in the appended claims.

Referring to the drawings: Figure 1 shows in a vertical section one form of my invention; and Fig. 2 shows in vertical section another form thereof.

45 Referring to the form shown in Fig. 1 the body 10 of the float is shown as of a flattened pear shape in vertical section and is preferably circular or approximately so in horizontal section. I attach to this body a 50 depending portion 11 at the bottom of which is carried a ballast weight or filling 12. The body of the float may be constituted of a wooden frame work 13 with a cork or other covering 14 thereover and an outer shell or

skin of suitable material such as rubber canvas or metal 15. I show the top of the depending portion 11 covered with a floor 16, and the entrance opening at the drawn-in top of the body is adapted to be closed by a removable closure 17; it being understood 55 that it is through this opening that persons enter the float, and that the closure 17 is then fitted and made secure in any suitable manner. A side opening 18 closed by suitable transparent material is provided, so 60 that persons within the float can make observations as to their surroundings.

As a means for obtaining ventilation within the float while at the same time preventing ingress of water thereto, I provide pipe 70 conduits 19 shown as two in number, and each having one branch 19^a extending straight upward through the float wall to some distance thereabove, and another branch 19^b extending diagonally upward 75 within the float from the junction point of the branch 19^a, the branches 19^b being perforated as at 20 for the dissemination of air therefrom. The lower portion of these pipes extend down into the depending extension 80 11 as seen at 21 so that in case the float should tilt over or waves dash some water in the branches 19^a it will run on down through the pipe extensions 21 into the depending extension 11 of the float from whence it 85 may be pumped out by a suitable pump 22 with an outlet 23 without the extension 11, and an operating handle 24 extending up through the floor 16. Thus it will be observed that an adequate supply of air is 90 always circulated into the float through the pipe branches 19^a, 19^b, the branches 19^a of course normally being above the water, while whatever small amounts of water may pass into the branches 19^a will not enter the body 95 of the float but will run down the pipes 19 and be emptied from their extensions 21 into the closed off hollow space of depending extension 11 whence it may be pumped 100 when convenient by the pump 22; the branches 19^b extending diagonally upward within the float, thus serving to introduce adequate amounts of air without liability of permitting the entrance of water.

Referring now to the form shown in Fig. 105 2, the float shell in this case is shown as of a general boat-like contour, being in shape practically that of two boats one placed over

the other as indicated at 27, 28, as a closure for the top thereof, the walls, of course, being continuous. In this form of the invention the float may rest either side up, and if perchance it should be upset, it can be quickly righted the other side up, with no serious inconvenience to the inmates. In this form I show sight openings 29, 30, closed by glass or other transparent material at both sides of the float so that one may be used whichever side up the float is disposed. A third intermediate sight opening 31 is shown near the other end of the float. In this form of the invention I show air inlet pipes 32, 33 similarly mounted to project upward and downward from the central portion of the float with air disseminating perforated branch pipes 34, 35 extending diagonally from the pipes 32, 33 outward toward the adjacent shell of the float, so that one set of these pipes is always operative to furnish air no matter which side up the float may be. Suitable valve cocks 36 may be provided in the pipes 32, 33, so that the one of these pipes which happens to be projecting downward can be closed to prevent the influx of water. As a means for pumping out any water that may enter through the air inlet pipe which is in service and projecting upward, I connect to the inner ends of these pipes, pipe connections which may be hose as indicated at 37, leading to the inlet end of a discharging pump 38 which is adapted to discharge the water through an outlet 39.

It is to be observed that both forms of my invention are simple in construction and that there is no mechanism interior of the float to get out of order or cause trouble by possible breakage. Further that the floats are so constructed that they may carry persons for a considerable period, if necessary, in perfect security until they are sighted and picked up. In practice, any convenient or desired means may be employed to project the floats away from the danger zone near a sinking ship but this means forms no part of the present invention and is therefore not herein shown.

I desire the present embodiment to be considered as illustrative and not restrictive, and the proportions and relative arrangement of parts in detail is also merely intended to typify any suitable arrangement in these respects adapted to carry out the essential attributes of the invention. I therefore refer to the appended claims rather than to the foregoing description to indicate the scope of the invention.

Having described my invention, what I

claim as new and desire to secure by Letters Patent is:

1. Life saving apparatus, comprising a normally closed float having provision to receive inmates, and equipped with a depending extension carrying a ballast weight and having a hollow portion closed off from the body of the float, and air inlet means comprising a pipe having one branch extending upward from within the float a substantial distance thereabove and another branch extending diagonally upward within the float with openings therein, said branches joining a substantial distance below the top of the float, and a pipe conduit leading downward from said branches to the hollow portion of said depending extension for the purpose stated.

2. Life saving apparatus, comprising a normally closed float having provision to receive inmates, and equipped with a depending extension carrying a ballast weight and having a hollow portion closed off from the body of the float, air inlet means comprising a pipe having one branch extending upward from within the float a substantial distance thereabove and another branch extending diagonally upward within the float with openings therein, said branches joining a substantial distance below the top of the float, and a pipe conduit leading downward from said branches to the hollow portion of said depending extension for the purpose stated.

3. Life saving apparatus, comprising a float of flattened pear shape with an entrance opening at its top equipped with a removable closure and a depending extension having a hollow portion closed off from the body of the float, air inlet means comprising a pipe having one branch extending upward from within the float to a substantial distance thereabove, and another branch extending diagonally upward from the first named branch a substantial distance below the top of the float, the latter branch being perforated, and a pipe conduit leading downward from the junction of said branches and emptying into the hollow portion of said depending extension for the purpose stated.

In testimony whereof, I have signed my name to this specification, in the presence of two subscribing witnesses.

BARTOL TRAVAGLIA.
